UNITED STATES PATENT OFFICE.

FRIEDRICH WILHELM KERN, OF ANTWERP, BELGIUM.

LIFE-BELT.

SPECIFICATION forming part of Letters Patent No. 731,058, dated June 16, 1903.

Application filed December 4, 1902. Serial No. 133,894. (No model.)

To all whom it may concern:

Be it known that I, FRIEDRICH WILHELM KERN, a subject of the German Emperor, and a resident of Antwerp, Belgium, have invented a certain new and Improved Life-Belt, of which the following is a specification.

The object of the present invention is a life-belt which permits a shipwrecked person furnished with one to instantaneously place it in use and to maintain himself for an indefinite period upon the water.

This apparatus comprises the belt proper provided upon each side of its middle part with a bladder or like animal membrane communicating with an apparatus for producing acetylene gas arranged as a front plate upon the belt and which allows the instantaneou inflation of the two bladders when required.

The drawings show, by way of example, a manner of carrying out this invention.

Figure 1 is an elevation of the belt opened out. Fig. 2 is a rear elevation of the acetylene-gas-producing apparatus. Fig. 3 is an inside view of the latter with one of its covers taken off. Fig. 4 is a section on A B of Fig. 5. Fig. 5 is a side elevation thereof. Fig. 6 is a detail. Fig. 7 is an elevation of the belt with the bladders inflated.

The life-belt is formed with two bladders *a* and *b*, treated with salt, vaseline, glycerin, whale-oil, and tallow. Each of these bladders is placed in a jacket *c*, made of any suitable tissue, such as velvet calico and the like, and sufficiently large to allow the inflation of the bladder covered by it. The two casings are fixed to the belt proper, *d*, furnished at one end with a buckle *e* and at the other with holes *f*, thus permitting the belt to be easily adapted to the body. Between the two bladders upon the belt is left a free space, upon which is attached, by means of two hooks *g* *h*, the acetylene-gas-producing apparatus *i*, to which these two hooks are attached. Each bladder is connected in a tight manner to one of the two tubes *n* and *o* of the gas apparatus. The latter comprises a small box, of copper or other appropriate metal, divided into two tight compartments *j* *k* by a partition *l*. A tube *m* passes through the partition *l* and opens into the compartments *j* and leads out of the box, where it is provided with a small shoulder and is screw-

threaded upon its outer side. This tube is brazed to the partition *l* and is provided with two ports *p*, the object whereof will be hereinafter described. Outside the box it is plugged up by a screw-cap *q* with the insertion of a small ring *r*. This plug *q* is provided axially with a hole, through which passes the spindle *s* of a small piston sliding inside the tube *m* and which normally closes the ports of the latter. This piston is held in place by means of a strip of tissue-paper folded several times and passing through an eyelet *u* upon the end of the spindle *s* and tightened by screwing up the screwed plug *q*. The compartment *j* is intended to contain water. It is provided with a hole for the entry thereof and which is closed by a screwed plug *V*.

The compartment *k* constitutes the generator and contains carbid of calcium, which is introduced therein by an opening made in the front cover of the compartment and normally closed by a plate *y*, fixed by means of screws *w*.

The person provided with a belt of this description can wear it at times when wrecks are most liable to occur, such as in foggy or stormy weather.

When a disaster takes place, it is necessary to tear the strip *r* of tissue-paper by pulling the string *Q*. The piston uncovers the ports *p*, and the water in the compartment *j* passes through the windows into the compartment *k*, wherein it attacks the carbid. Instantly a quantity of gas sufficient to inflate the two bladders is disengaged. This gas passes through the tubes *n* and *o* into the said bladders. The bladders inflated in the described manner support the wearer in a perfect manner above the water.

If the wearer jumps into the water without pulling the string *q*, the freeing of the piston is performed automatically in the following manner: The compartment *j* contains besides water a coiled spring *t*, bearing upon one hand against the plug *V* and on the other against the piston *s*.

As it has already been said, the piston-spindle *s* is normally maintained by the strip of tissue-paper arranged in the cap *q*. The wearer being immersed to the waist, in water the tissue-paper will be dissolved, and the

piston, being thus freed, is pushed by the pressure of the compressed coiled spring contained with the water in the compartment *j*, opens the ports *p*, and the production of gas 5 instantly takes place.

In order to make the belt more compact, the bladders are after being treated folded and compressed upon the belt proper, to which they adhere after their desiccation, the 10 pressure of the gas at their inflation being sufficient to detach them. The casing of tissue is generally when not in use also folded upon the belt and is held thereupon by means of a very thin india-rubber band, which tears immediately inflation takes place.

Having now fully described my invention, what I claim, and desire to secure by Letters Patent, is—

In a device of the character described the 20 combination with a belt of a pair of inflatable bodies secured to said belt, means con-

nected with said bodies for inflating the same, comprising a casing having two outlets therein, a partition forming compartments therein, one of said compartments 25 adapted to contain a gas-evolving medium, a tube, having ports therein, connecting said compartments, a piston therein adapted to normally close said ports, the other of said compartments holding a liquid adapted upon 30 admission to the first-named compartment to produce the gas for inflation of the bodies and means for opening the said ports to permit said liquid to enter the gas-producing compartment when the device is to be used, substantially as described.

In testimony whereof I have hereunto set my hand in presence of two witnesses.

FRIEDRICH WILHELM KERN.
